UNITED STATES PATENT OFFICE.

JACOB P. BROWN AND JOSEPH A. STRANG, OF PATERSON, NEW JERSEY.

SHUTTLE TENSION.

Application filed October 24, 1923. Serial No. 670,582.

To all whom it may concern:

Be it known that we, JACOB P. BROWN and JOSEPH A. STRANG, citizens of the United States, residing at Paterson, in the county of Passaic and State of New Jersey, have invented certain new and useful Improvements in Shuttle Tensions, of which the following is a specification.

This invention relates to loom shuttle tensions, and particularly to that class of such devices in which a spring-actuated lever is provided with a series of guides which cooperate with another and fixed series of guides, alternating with the first series, in maintaining tension on the thread, which is adapted to extend in engagement with all the guides. The principal object is to provide a tension device, as said lever, which shall be simple and inexpensive in construction and have its guides readily removable therefrom and replaceable by others when they become worn, as by the cutting action of the thread.

We have shown the invention by way of example in the accompanying drawing in two forms, and it may be here stated that the invention in part broadly consists in a tension device including a body member having openings therein at intervals, guides resting on said member at one side thereof and projecting through said openings and at the other side of the member, and means, at and bearing against the other side of said member and extending through the several guides, for securing them to said member.

In said drawing, Figs. 1 to 8 on the one hand and Figs. 9 to 12 on the other show the two different forms of the invention.

Fig. 1 showing the first form in side elevation in position in a shuttle;

Fig. 2 being a plan of the blank from which the body member of the device is formed;

Fig. 3 a side elevation of the guides-securing tongue constituting, in the illustrated example, the means already mentioned;

Fig. 4 is a top plan of the device;

Fig. 5 is a section on line 5—5, Fig. 4;

Fig. 6 is an underneath plan of the device;

Fig. 7 is an end elevation thereof;

Fig. 8 is a section on line 8—8, Fig. 5;

Fig. 9 is a top plan of the other form of the device;

Fig. 10 is a section on line 10—10, Fig. 9;

Fig. 11 is an underneath plan of the device shown in Fig. 9; and

Fig. 12 is a section on line 12—12, Fig. 10.

The loom shuttle *a* has its cavity *b* traversed by a fulcrum pin *c* and the usual pins *d* forming the mentioned fixed series of guides. It also has, suitably secured to a pin *e*, the rubber or other elastic device *f* adapted to shift the lever equipped with the series of guides which coat with the series *d* contrary to the action of the thread *A* to be controlled. The improved tension device (herein embodied in the lever) is constructed as follows:

Having reference, first, to the first eight figures of the drawing: An elongated stiff sheet blank *g* is provided, the same having transversely elongated openings *h* arranged in a lengthwise series, equally spaced from each other. At each side of the blank, opposite each opening, is a projection *i*. The openings and projections occupy only a portion (as about one-half) of the length of the blank, the remainder of which is left plain. This plain end-portion of the blank is formed into a curl *j*, adapted to afford a fulcrum for the lever on the fulcrum pin *c* of the shuttle, and its extremity is bent downward, as at *l*, and may be provided with a hole *m* to receive the end of the elastic device *f*. Between the pairs of projections *i* the material of the blank is pinched or folded, as at *n*, Fig. 4, on a central longitudinal axis so that the salient side of the fold is up; this leaves a downwardly open channel *o* (Fig. 7). The projections *i* are each bent on a transverse central axis (Figs. 4 and 7) so that the salient side of the bend is in each instance down; this, as to each pair of thus-bent projections, leaves a transverse channel or transversely elongated socket *p* (Fig. 4), the bending resulting further in a desirable curving upward of the ends of each transverse portion of the blank which includes a pair of the projections *i*, as shown by Figs. 7 and 8. The guides *q*, which are here in the form of circular (as ordinary glass) eyelets, are adapted to be seated in the sockets *p*, as shown in Figs. 1, 4, 6, 7 and 8 and in so doing they project through the material of the body member formed from the blank as stated, to wit, through the openings *h*, resting against the top side and protruding (into the chan-

nel o) at the underneath side of said member. To secure the eyelets in place we provide the strip or tongue r of stiff elongated material which is introduced endwise into the channel o from its free end and is passed through the several eyelets, (in the present example, actually through their thread apertures q') beneath said member. By bending up its entering end, as at r' , this tongue may be made to bear against said member and thus by friction be retained in place; it may have a hook r'' at its other end by which it may be caught in removing it. Each guide is thus securely though removable held in place. The sides of the pair of sockets which receive each eyelet assist, as will be obvious, in keeping the eyelet in a definite upright position.

Referring, now, to Figs. 9 to 12, the body member is formed from an elongated blank s of sheet material having transversely elongated openings s' in one end portion thereof and its other end portion formed with a curl t and with its extremity u bent downward, the curl t and extremity u corresponding in form and function to the curl j and extremity l already described. In this case the openings s' are formed by transversely slitting the material of the blank on pairs of parallel lines and pressing down such material between the lines in each pair, as indicated at v in Fig. 10; the part of the material thus bent downward may be in each instance channeled lengthwise thereof as shown in said figure. The guides w , here also in the form of circular eyelets, are respectively set in the openings s and seated in the channeled depressed portions v . The guides having thus been arranged in their settings, a tongue x , substantially the same as that already described, is entered at the underside of the body member and through the several guides. The channeling of the depressed portions v in this instance assists in keeping the guides in a more or less definite upright position.

In another aspect of our invention the body member may be regarded as recessed at intervals, with the guides seated in the recesses (formed by the openings h or s') and stiff attenuated means (as r or x) to hold the guides in place extending longitudinally of the series of guides and through the latter and also through said member at intervals.

We claim:

1. A tension device including a body member having openings therein at intervals, guides resting on said member at one

side thereof and projecting through the respective openings and at the other side of said member, and means, at and bearing against the other side of said member and extending through the guides, for securing them to said member.

2. A tension device including a body member having openings therein at intervals, guides having thread apertures and resting on said member at one side thereof and projecting through the respective openings and at the other side of said member, and means, at and bearing against the other side of said member and extending through the apertures of the guides, for securing them to said member.

3. A tension device including a body member having openings therein at intervals, guides resting on said member at one side thereof and projecting through the respective openings and at the other side of said member, and a substantially straight stiff holding device at and bearing against the other side of said member and extending through the guides.

4. A tension device including a body member having openings therein at intervals, guides resting on said member at one side thereof and projecting through the respective openings and at the other side of said member, and means, at and bearing against the other side of said member and extending through the guides, for securing them to said member, said member having transverse channels in which the guides are respectively seated.

5. A tension device including a body member formed from an elongated piece of stiff sheet material channeled lengthwise and having openings at intervals therein and each traversing its bend, guides received in the openings and resting on said member at the side thereof corresponding to the salient side of its bend, and means, arranged in the channel of said member and extending through the guides, for securing the guides to said member.

6. A tension device including a body member formed with a series of recesses at intervals, guides seated in the recesses, and stiff attenuated means to secure the guides to said member extending longitudinally of the series of guides and through the latter and also through said member at intervals.

In testimony whereof we affix our signatures.

JACOB P. BROWN.
JOSEPH A. STRANG
